OR D 12,421

DESIGN FOR A CASKET-HANDLE.

Design No. 12,421, dated August 16, 1881.

UNITED STATES PATENT OFFICE.

HENRY E. TAYLOR, OF NEW YORK, N. Y.

DESIGN FOR A CASKET-HANDLE.

SPECIFICATION forming part of Design No. 12,421, dated August 16, 1881.
Application filed July 16, 1881. Term of patent 7 years.

To all whom it may concern:

Be it known that I, HENRY E. TAYLOR, a citizen of the United States, residing at New York, in the county and State of New York, have invented a new and original Design for Casket-Handles, of which the following is a specification.

This invention is a design for the handles of caskets, consisting of an annular ear-plate or escutcheon and divergent leaves radiating from the inner portion of the ear-plate beyond its outer edge; also, of beaded heads on the edge of the ear-plate, alternating with the divergent leaves; and, further, of a rectilinear handle-bar having scaled tips.

The accompanying photographic illustration shows the design in front view.

The letter A designates the ear-plate or escutcheon; B, the divergent leaves; C, the beaded heads; and D, the handle-bar, having tips D'.

The ear-plate A is the part receiving the swinging ears of the handle-bar D, and serving to secure the whole to the casket, and it has an annular shape. The face of this ear-plate is ornamented with border-lines and radial lines interspersed with graining.

The divergent leaves B radiate from the inner portion of the ear-plate A beyond its outer edge, and they are ornamented by end foils, e, face-buttons f, and face cross-lines.

The beaded heads C are on the edge of the ear-plate A, the same alternating with the leaves B, and their beads are on the edges of

the heads. The faces of these heads C are ornamented by a group, i, of beads smaller than the main or edge beads.

The handle-bar D is rectilinear, and its tips D' are provided with scales o, which project toward each other, leaving a space between them, which is ornamented with graining.

By these characteristic features a novel appearance is imparted to the handle, whereby it can be readily distinguished from those now generally used.

What I claim as new, and desire to secure by Letters Patent, is—

1. The design for a casket-handle, consisting of an annular ear-plate or escutcheon and divergent leaves radiating from the inner portion of the ear-plate beyond its outer edge, as shown and described.

2. The design for a casket-handle, consisting of an annular ear-plate or escutcheon, divergent leaves radiating from the inner portion of the ear-plate, and beaded heads alternating with the divergent leaves, as shown and described.

3. The design for a casket-handle, consisting of a rectilinear handle-bar having scaled tips, as shown and described.

In testimony whereof I have hereunto set my hand and seal in the presence of two subscribing witnesses.

HENRY E. TAYLOR. [L. S.]
